(57) **CLAIM**

The ornamental design for an oral care implement, as shown and described.

DESCRIPTION

FIG. 1 is a right front perspective view of an oral care implement according to the new design;
FIG. 2 is a left front perspective view thereof;
FIG. 3 is a right rear perspective view thereof;
FIG. 4 is a left rear perspective view thereof;
FIG. 5 is a front view thereof;
FIG. 6 is a rear view thereof;
FIG. 7 is a left side view thereof;
FIG. 8 is a right side view thereof;
FIG. 9 is an enlarged top view thereof;
FIG. 10 is an enlarged bottom view thereof;
FIG. 11 is an enlarged right front perspective view of the head; and,
FIG. 12 is an enlarged right rear perspective view of the head. The claim consists of the cleaning elements shown on the front of the head. The broken lines showing the rest of the head and the handle illustrate portions of the oral care implement that form no part of the claimed design.
